ABSTRACT OF THE DISCLOSURE

A container washing machine having two sections, one of which is provided for washing and the other of which is provided for removing containers from the machine and adding containers to the machine, having means to expose the containers in one section of the machine for removing and adding containers while enclosing the containers in the other section of the machine for washing the containers, is disclosed herein.

Cleaning machines for washing the outsides and insides of containers are known. Machines for cleaning small numbers of pieces per hour mostly consist of stationary sheet-steel cases, with doors or openings, and with appliances for the containers and nozzles properly arranged for cleaning outsides and insides of the containers.

The disadvantage of these machines is that they cannot be used very economically, for time is lost in exchanging containers after finishing a cleaning.

Machines for cleaning higher numbers of pieces per hour are made rotatable, as for example known rotary bottle cleaners.

The disadvantage of these machines is that they are expensive to manufacture and cumbersome in construction by the necessary driving gear for rotation. Besides, these mechanical driving gears are susceptible to breakdowns.

To exclude those disadvantages a cleaning machine is recommended according to the invention, by which on the one hand the operating time will be utilized completely for cleaning while on the other hand no rotation process by motor power is necessary.

According to one embodiment of the invention the machine is composed of a case with two to four or more chambers, each with an opening, through which the containers to be cleaned are set into the appliances.

Since a machine having two chambers is preferred, such embodiment will be described in more detail. One chamber opening is closed by a sliding door. By sliding that door one chamber is opened and the other one is closed. A cleaning only takes place on those containers which are within the chamber closed by the sliding door, while containers which have been cleaned and which are to be cleaned may be exchanged in the opened chamber. Since cleaning is still effected in one chamber, while the containers are replaced in the other one, the capacity of the machine is completely utilized. The invention has however the advantage, that only one pump system and one electric automatic modulating system is required as in the simpler known apparatus, and that in spite of this the cleaning capacity is doubled. By moving sliding door, valves are operated over contacts or cams (operating clock valves), which permit cleaning only within the closed chamber.

There are different methods; the foregoing is only an example. The machine may have various forms, such as rectangular and round. The chambers may have a different capacity. An embodiment of the invention is described in more detail in the attached drawing.

2

FIGURE 1 is a front elevation of one embodiment of the invention;

FIGURE 2 is a plan view of the embodiment shown in FIGURE 1;

FIGURE 3 is a front elevation of a second embodiment of the invention in which a container and a circular bearing have been cut away to reveal the operation of the apparatus;

FIGURE 4 is a plan view of the embodiment shown in FIGURE 3.

In FIGURE 1, the numeral 11 generally designates the case of the machine in which is defined the chamber 12 and behind the door 17 the chamber 32. Within the chamber 12 are containers 13 and 14 in the appliances 15 and 16, while containers 18 and 19 are being cleaned inside the chamber 32. After finishing of cleaning inside the chamber 32 the door 17 will be pushed into a position in front of the containers 13 and 14, so that chamber 32 will be opened and chamber 12 will be closed. The cleaning procedure inside the chamber 12 is then started. The containers 18 and 19 then are freely accessible and may be changed with other ones for cleaning. The pipes with the nozzles for the outlet of cleaning compounds are designated by 30 and 31.

In FIGURE 2, 11 shows the case from above and 17 the sliding door. The dividing wall between the chambers 12 and 32 is designated by 20. The cleaning compound flows through the pipe 21. The valves 22 and 23 will be controlled by the stop switches 24 and 25 by the door 17. For example, if the door 17 is in the position at the stop switch 24, as shown in FIGURES 1 and 2, the valve 22 is closed through a contact or a dialling device and valve 23 is opened. If the contact with the stop 24 is terminated by displacing the door 17, the valve 23 closes too, and the valve 22 opens if the door 17 operates the stop-contact 25.

Another example is described in FIGURES 3 and 4. In FIGURE 3, the numeral 40 designates the case having a frame 41, which is turnable round the axle A—B. At the frame 41 two semicircles of pipe 42 and 43 are attached as shown in FIGURE 4. On 42 and 43 the containers 61—70 are attached to be cleaned. The cleaning compound gets through the hollow pipe 51 either into the semicircle 42 or into the semicircle 43, only into that one which is inside the machine 40.

In FIGURE 4 is shown the semicircle 42, on which are attached containers 61 through 65 which are being cleaned. After finishing the cleaning procedure the frame 41 will be turned until the semicircle 43 is inside the machine case, and now the containers 66—70 will be cleaned. During a cleaning procedure it is possible to change outside the machine case the cleaned containers for more containers to be cleaned.

The embodiments of the invention in which an exclusive property or privilege is claimed are defined as follows:

1. A cleaning machine for containers, comprising a case having at least two chambers, at least one of said two chambers being configured for washing containers, and at least one of the two chambers being configured for the ready exchange of cleaned and uncleared containers; means to supply cleaning fluid selectively to the chambers; and means to facilitate the flow of cleaning fluid to one chamber while preventing the flow of cleaning fluid to the other chamber; wherein the chambers comprise two similar chambers having openings facilitating placement of containers within the chambers and having closing means for the openings, the closing means being inter-related whereby closing one chamber effects the opening of the other chamber, and the closing means being connected to the means to facilitate the flow of cleaning fluid, whereby the closing of one chamber facilitates the flow of

cleaning fluid to that chamber, and whereby the opening of the other chamber prevents the flow of cleaning fluid to that chamber.

2. The cleaning machine of claim 1 comprising:
 first and second chambers having open fronts and being arranged in adjacent side by side relationship; 5
 a track mounted on the open fronts of the adjacent chambers;
 a sliding door mounted on the track for selectively closing one or the other of the chambers;
 first and second cleaning fluid supply lines respectively connected to the first and second chambers and to a source of cleaning fluid; 10
 first and second valves mounted respectively in the first and second supply lines;
 a first switch mounted in the track adjacent the first chamber;
 a second switch mounted in the track adjacent the second chamber; and
 first and second communication circuits inter-connected 15
 to the respective first and second valves and switches, whereby sliding the door in front of the first chamber closes the first switch and operates the first com- 20

munication system, thereby actuating and opening the first valve to supply cleaning fluid to the first chamber, and whereby sliding the door away from the second chamber opens the second valve cutting off the second communication system, which closes the second valve preventing the flow of cleaning fluid to the second chamber.
